UNITED STATES PATENT OFFICE.

GEORGE J. HAGAN, OF PERRYSVILLE, PENNSYLVANIA, ASSIGNOR TO GEORGE J. HAGAN COMPANY, OF PITTSBURGH, PENNSYLVANIA, A CORPORATION OF PENNSYLVANIA.

BAR AND SHEET HEATING FURNACE.

Application filed July 2, 1923. Serial No. 649,009.

To all whom it may concern:

Be it known that I, GEORGE J. HAGAN, residing at Perrysville, in the county of Allegheny and State of Pennsylvania, a citizen of the United States, have invented or discovered certain new and useful Improvements in Bar and Sheet Heating Furnaces, of which improvements the following is a specification.

10 The invention described herein relates to certain improvements in heating furnaces employed in the manufacture of sheets and the invention has for its object the combination of a combustion chamber or fire box connected with a portion or portions adapted for the heating of bars and also with a portion adapted for the heating of sheets with means for regulating the flow of products of combustion to the respective portions. The invention is hereinafter more fully described and claimed.

In the accompanying drawings forming a part of this specification, Figure 1 is a sectional plan view of a furnace embodying the improvements claimed herein;

Figure 2 is a sectional elevation, the plane of section being indicated by the line II—II, Figure 1;

Figures 3 and 4 are views similar to Figures 1 and 2 showing another embodiment of the invention; and

Figure 5 is a top plan view of the furnace shown in Figures 3 and 4.

In the practice of the invention the furnace is so constructed as to provide two heating chambers, one of the heating chambers, as 1, being especially adapted for the heating of sheet-bars and the chamber 2 for the heating of sheets, either in packs or in singles. These chambers are preferably arranged side by side and have a common side wall 3 which also forms one of the side walls of the combustion chamber of fire-box 4. While a stoking mechanism 4^a is shown for the supply of fuel to the combustion chamber, other forms of fuel, liquid or gaseous, may be employed. One end of the chamber 1 is provided with a door and with mechanism 5 for feeding bars into and through the chamber which is also provided with a door 6 at its discharge end. The chamber 2 is provided with a door 7 for charging and removing of material, the doors 6 and 7 being arranged at the same end of the furnace. 55 The combustion chamber 4 is connected to

the pair heating chamber 1 through the port or opening 8 and products of combustion from the combustion chamber pass directly into the sheet heating chamber 2 over the bridge wall 9. Adjacent to the discharge end of the pair heating furnace, ports 10 are provided for the escape of products of combustion, said ports being connected to flues 11 leading to the vertical flue 12 which is connected at its upper end to the flue 13 leading to the stack. A suitably arranged damper is provided for controlling the flow of products of combustion through the chamber. In the construction shown a damper 14 is arranged in the flue 13. The products of combustion pass from the sheet heating chamber through ports 15 connected to flues 16 which in turn are connected to a common flue 17, passing under the heating chamber. This flue is connected at its end 75 to up-take flues 18 which in turn are connected to flues 19 leading to the stack, and in the flue 19 is arranged a damper 20 for regulating the flow of products of combustion from the sheet heating chamber. 80

In lieu of providing only one pair-heating chamber, it is preferred that two such chambers 1^a should be employed and arranged on opposite sides of the sheet heating chamber 2. These pair-heating chambers 85 are extended beyond the sheet heating chamber and intermediate of these extensions, and in the rear of the sheet heating chamber is arranged the combustion chamber 4^a. In this construction products of combustion 90 pass from the combustion chamber 4^a over the bridge wall 9 into the sheet heating chamber and thence through ports 15^a and flues 16^a, 17^a, 18^a and 19^a as hereinbefore described, to the stack. The pair-heating 95 chambers are connected to opposite sides of the combustion chamber by ports 8 and the products of combustion escape from the front portions of the pair-heating chambers through ports 10^a, flues 11^a, 12^a and 13^a to 100 the stack, and the flow of the products of combustion is controlled by dampers 14^a as hereinbefore described, in connection with the construction shown in Figures 1 and 2.

It will be observed that in the construction 105 shown and described herein, the flow of the products of combustion and consequently the amount of heat passing through pair and sheet heating chambers can be properly proportioned so as to properly heat the charges 110

in the respective chambers. As a general thing, the quantity of material in the pair-heating chambers will be greater than that in the sheet heating chamber and the area exposed to the action of the products of combustion will be less and hence a higher temperature should be maintained in the pair-heating chamber or chambers than will be required for heating the sheets which have the larger exposed area, in the sheet heating chamber or chambers.

I claim herein as my invention:

1. A furnace having in combination a combustion chamber, a sheet heating chamber communicating at one end with the combustion chamber and having a charging and discharging opening at its opposite end, an open ended bar heating chamber communicating with the combustion chamber, means for moving bars through said chamber, flues or passages for conducting products of combustion from the respective heating chambers, and dampers whereby the flow of products of combustion through the respective chambers may be independently regulated.

2. A furnace having in combination a combustion chamber, a sheet heating chamber communicating at one end with the combustion chamber and having a charging and

discharging opening at its opposite end, a bar heating chamber arranged along side of the sheet heating chamber and having openings at its ends, means for feeding bars through the chamber, a port or passage connecting the combustion chamber to the heating chamber at a point adjacent to the end at which the bars are charged, flues or passages communicating with the respective heating chambers at points adjacent to their discharging ends and dampers adapted to regulate the flow of products of combustion through said chambers.

3. A furnace having in combination a sheet heating chamber, bar heating chambers extending along opposite sides of the sheet heating chambers, a combustion chamber in the rear of the sheet heating chamber and intermediate the bar heating chambers, and connected to the sheet and bar heating chambers, a stack, independent flues extending from the several heating chambers to the stack and dampers adapted to regulate the flow of products of combustion through the several chambers.

In testimony whereof, I have hereunto set my hand.

GEORGE T. HAGAN
